UNITED STATES PATENT OFFICE

JOSEPH HARRINGTON, OF RIVERSIDE, ILLINOIS, ASSIGNOR TO JOSEPH HARRINGTON COMPANY, OF HARVEY, ILLINOIS, A CORPORATION OF ILLINOIS

APPARATUS FOR AND METHOD OF HEAT TREATING CERAMIC MATERIALS

Application filed April 22, 1929. Serial No. 357,099.

My invention relates generally to apparatus for and methods of heat treating ceramic materials and particularly to kilns and methods of heat treating ware within kilns.

5 It has heretofore been a common practice to employ kilns in which fire boxes with grates have been arranged in spaced relation along the lower section of the kiln wall. In employing such types of kilns numerous disadvantages are presented. These kilns employ natural draft and the gases from the fire boxes or pockets pass upwardly inside the dome of the kiln and then pass downwardly through the perforate floor to an 15 underground flue. Under these natural draft conditions the hot gases will naturally pass downwardly along the path of least resistance and this frequently causes a laning of the gases from some point within the kiln toward another point of exit. That is to say, instead of the hot gases being uniformly diffused within the kiln, they are drawn downwardly through localized areas. During 20 the water-smoking period, that is, the period when the ware is initially subjected to heat, the only vehicle for conveying water away from the ware is the small quantity of hot gas which is generated in the above mentioned fire boxes and therefore considerable 25 time must be expended in drying the ware. During this water-smoking period the relatively small quantity of hot gases rise from the fire boxes to the top of the kiln. It will be understood that the ware, when initially 30 placed within the kiln, is cold and damp and that hot gases from the fire pockets serve to drive off a certain amount of moisture from the top layers of the ware. The gas soon becomes saturated and as it descends within the 35 kiln and is carried into contact with the lower moistened ware, condensation must necessarily take place. In other words, an air vehicle in sufficient quantity is not provided for carrying away the moisture from the 40 ware and hence a redepositing of the moisture takes place. Obviously, under such conditions the ware must be subjected to the hot gases for a relatively long period in order 45 that all of the moisture might be removed.

50 In general, one of the primary objects of

my present invention is to provide a simple and durably constructed apparatus by means of which methods of heat treating ceramic materials may be efficiently practiced to the end that the above mentioned and other disadvantages and inconveniences may be avoided. 55

More specifically, it is an object of my present invention to provide means and methods whereby heated gases may be effectively tempered and then uniformly diffused within a heat treating chamber. 60

Another object of my invention is to properly and positively control the introduction of excess air into the heat treating chamber, which air will serve efficiently for vehicle purposes. 65

Another important object of my present invention is to provide methods and means whereby the interior of a heat treating chamber or kiln may be subjected to pressure above atmospheric pressure so as to positively insure uniform diffusion of heat to all parts of the kiln chamber. 70

Still another and more specific object of my invention is to introduce excess air for vehicle purposes which has preliminarily been conditioned, and I contemplate introducing said conditioned air into an enclosure containing the ware in such a manner as to insure increased efficiency in the burning of the ware. 75

Still another object of my invention is to eliminate the smoke nuisance which has heretofore been experienced in connection with burning the ware and to this end I propose 80 to employ, in combination with an improved kiln construction, an automatic stoker of improved practical design. 85

These and numerous other objects and advantages will be more apparent from the following detailed description when considered in connection with the accompanying drawings, wherein: 90

Figure 1 is a vertical transverse sectional view of a kiln which is representative of one embodiment of my invention and by means of which my improved method of heat treating ceramic materials may be effectively practiced, said section being taken substantially along the line 1—1 of Figure 2; 95 100

Figure 2 is a plan view of the kiln construction shown in Figure 1;

Figure 3 is an enlarged horizontal sectional view taken substantially along the line 5 3—3 of Figure 1, which illustrates in plan the manner in which the stoker is enclosed in an air-tight compartment so as to maintain the air pressure outside of the stoker slightly greater than the pressure within the stoker;

10 Figure 4 is a diagrammatic plan view disclosing the manner in which a plurality of heating devices constructed in accordance with the teachings of my invention may be coupled together so as to make for increased 15 operating efficiency; and

Figure 5 is also a diagrammatic representation disclosing a side view of Figure 4.

Referring now more in detail to the drawings wherein like numerals have been employed to designate similar parts throughout the various figures, it will be seen that one embodiment of my invention contemplates the provision of a dome-shaped kiln which I have indicated generally by the numeral 10. 20 This kiln 10 may be constructed of any suitable heat resisting material of the type which has heretofore been employed in kiln constructions. A burning or heat treating chamber 12 is enclosed by the semispherical 25 wall 14 of the kiln and the floor 16 of said kiln is provided with a plurality of openings or vents 18 which communicate at their lower extremities with a common discharge conduit or passageway 20. It is to be noted that 30 the inner surface of the kiln wall 14 is free from any projections or obstructions and therefore I am able to pile ware within the kiln, which in the particular instance constitutes brick 22, so that said ware is positioned 35 in close proximity to the inner surface of said wall. In conventional types of dome-shaped kilns fire boxes are spaced along the inner surface of the kiln wall adjacent the floor and obviously considerable space is taken up 40 by these fire boxes or pockets. My present invention eliminates the necessity of providing these fire boxes and hence provides additional space for accommodating the ware. The upper central portion of the kiln wall 14 45 is provided with an opening 24 which communicates with a flue or intake passageway 26.

This flue or passageway 26 communicates at its lower extremity with the combustion chamber 28 of an automatic stoker 30 later to be described. Disposed along the conduit 26 are a plurality of pipes 32 which are all connected to a common pipe or conduit 34. This conduit 34 is connected with the discharge side of a suitable air supplying mechanism or pump 36 and it will thus be apparent that air supplied by said mechanism will be directed through the agency of the pipes 32 and 34, into the passageway or flue 26. To 50 control the amount of excess air introduced

within the flue 26 I provide each of the pipes 32 with suitable dampers or valves 38 which may be controlled from any convenient point as for example by means of chains 40, Figure 1. A chain or belt 42 is associated with the shaft of each damper 38. Each of these belts 42 is connected with a companion shaft 44, which shaft is in turn connected with its companion chain 40. Thus, the position of the dampers 38 may be independently actuated by merely moving the corresponding chain 40. The means for controlling the position of the dampers 38 which has just been described is merely illustrative of one system which may be employed for controlling the introduction of excess air within the flue and obviously my invention is not limited to the specific described apparatus but contemplates any practical means for efficiently controlling the introduction of excess air into the flue.

Reference has heretofore been made to the automatic stoker which is designated generally by the numeral 30 and in this connection it might be stated that my present invention does not relate to the stoker per se, as this stoker mechanism is described and claimed in my copending application, Serial No. 340,924, filed February 18, 1929. A more comprehensive and detailed description of the stoker proper may be had by referring to my aforementioned copending application. This stoker 30 comprises a suitable fuel hopper 46 which is adapted to direct fuel downwardly onto a horizontally reciprocable grate section 48. Fuel which is deposited upon this reciprocable grate section 48 is uniformly advanced through the combustion chamber 28 through the inter-action of other grate sections 52 and 54 which cooperate with the grate section 48. In order to maintain the air pressure surrounding the stoker 30 at a slightly greater pressure than the pressure within the stoker I surround said mechanism by a suitable sealing wall 56. A chamber 58 which is enclosed by the sealing wall 56, is supplied with air through the agency of a suitable motor driven pump 60. The air pressure within the chamber 58 is maintained at a slightly greater pressure than the pressure within the stoker and hence proper draft conditions upwardly through the fuel bed supported by the stoker grates is constantly maintained. The advantages resulting from the provision of the sealing wall 56 will be apparent when it is understood that it is very difficult to construct a furnace or stoker which is free from leaks at all points. Even the porous structure of the materials used in the construction of the furnace might be sufficient to establish a certain amount of leakage. Hence, by subjecting the entire stoker unit to an increased external pressure, leakage through the stoker walls is positively prevented.

In practicing my improved method by means of the above described apparatus, the ware or brick 22 is first piled or stacked within the kiln chamber 12, space being provided 5 between the stacked ware so as to permit the hot gases to permeate the entire stack. This ware is also arranged so as to permit the floor openings 18 to supply means of communication between the chamber 12 and the 10 discharge passageway 20. After the ware has been properly positioned within the kiln, the wall of said kiln is closed and heat from the stoker 30 is directed into the flue 26. The initial heat treatment to which the ware is 15 subjected is commonly known as the water-smoking period. During this period the moisture in the ware or brick is driven off and in driving off the moisture by the introduction of heated gases, care must be 20 exercised so as not to heat the ware too suddenly because the application of intense heat might result in causing the ware to crack. As the heated gases rise within the flue 26, said gases are diluted by the introduction of 25 cool air which is supplied from the fan 36. During this water-smoking period I prefer to control the dampers 38 so as to effect the introduction within the flue 26 of a considerable volume of excess air which dilutes and 30 tempers the hot gases issuing from the combustion chamber 28. In order to readily ascertain the exact temperature of the heated air and gases which pass through the kiln opening 24, I make use of a conventional 35 pyrometer which I have designated generally by the numeral 62, Figures 1 and 2. This pyrometer may be connected to a suitable recording or indicating instrument 64 positioned so that it may be conveniently observed 40 by an attendant. By observing the temperature indicated, the attendant may control the introduction of cool air into the flue 26 and may also increase or decrease the rate of combustion within the stoker. In other 45 words, my invention contemplates the accurate and positive control of the temperature at the point where the hot gases are introduced within the kiln chamber. The introduction of the excess volume of air not 50 only causes a dilution of the hot gases but also causes a decrease in the resultant temperature and by proper adjustment of the above mentioned parts a relatively large volume of air at the proper temperature may 55 be introduced within the kiln chamber during the water-smoking period. It will be apparent that if a sufficient volume of air at a fairly high temperature is employed as a vehicle, the moisture taken up thereby will 60 be quickly drawn off through floor openings or vents 18 and thence through the discharge passageway 20. This method of introducing excess heated air as a vehicle into the central upper portion of the kiln chamber 65 should be clearly distinguished from the conventional methods of water-smoking brick, tile and the like. In methods heretofore practiced the hot gases from the fire boxes or pockets spaced along the inner periphery of the kiln adjacent the floor rise 70 within the kiln chamber and quickly take up their volume of moisture. In other words, no excess air is present to be used as a drying vehicle. Air at a given temperature obviously will carry in suspension a certain limited weight of moisture and when this limit has been reached and the temperature is then lowered, condensation must necessarily take place. By employing my improved 75 method of heat treating I am able to introduce a sufficient supply of heated excess air to take up moisture from the ware and carry it out of the kiln chamber without any condensation. The removal of moisture from the ware by practicing my improved method greatly reduces the duration of the water-smoking period and the heat supplied from the combustion chamber 28 is very efficiently employed. After the moisture has been 80 driven off by this initial heat treating process, the temperature of the introduced gases may be raised. This can very easily be accomplished by adjusting the dampers 38 and also by varying the draft conditions within the stoker mechanism 30. The introduction of hot gases under pressure at the top of the kiln chamber and at the central portion thereof insures uniform diffusion of heat 85 throughout the entire kiln chamber. By introducing the hot gases under pressure as above described, no localized areas or lanes of hot gases will be present within the kiln chamber as is experienced in conventional types of kilns employing the natural draft principle. The attendant may conveniently 90 manipulate the chains 40 and the rate of combustion within the stoker mechanism 30 may be controlled in order to maintain constant predetermined temperature of the hot gases introduced within the kiln chamber. The 95 positive control of the temperature enables the ware to be uniformly burned or heat treated and the period of heat treatment may be considerably reduced. After the ware has 100 been subjected to the required heat treatment, the kiln wall may be opened and said ware removed. A new supply of ware may be stacked within the kiln and subjected to heat treatment in the manner described. Thus batches of ware such as brick, tile and 105 the like may be periodically burned in a very efficient and practical manner. 110

Attention is directed to the fact that the apparatus just described presents a system in which the heated gases are continuously subjected to a pressure above atmospheric pressure. In other words, the air vehicle and hot gases introduced within the kiln chamber are always at a pressure above atmospheric pressure. Introducing hot gases 115 120 125 130

within a heating chamber or kiln under pressure, positively insures uniform diffusion of said gases throughout the extent of the kiln. That is to say, when the hot gases 5 are forced into the kiln, they will instantly stratify so that the lighter gases will always be at the top and the density will increase as lower levels are approached. This stratification will be absolutely uniform and hence 10 all the corners of the kiln will be reached and the possibility of any laning of the gases will be precluded. This laning effect which has heretofore been experienced in using conventional types of natural draft kilns results 15 from the presence of negative pressures within the kiln chamber, that is, pressures below atmospheric pressure. The existence of negative pressures will naturally cause a surge of hot gases toward the negative 20 zone and hence make for non-uniform diffusion of the gases within the kiln. My invention enables the avoidance of such deleterious effects.

In Figures 4 and 5 I have diagrammatically disclosed the manner in which two or more heating devices of the type described may be coupled together. For purposes of illustration I have designated a pair of coupled kilns generally by the letters A and B. Thus, 25 as indicated by the directional arrows, hot gases from the combustion chamber 28 of the kiln unit A will pass through the flue 26 and downwardly within the kiln chamber 12. From the bottom of the kiln chamber 12 30 the gases are directed through the discharge passageway 20 in the manner already described. The opposite extremity of this passageway 20 communicates with a passageway 26a which will direct the hot gases into 35 the upper end of the kiln chamber 12 at the left of Figures 4 and 5. The heated gases then pass downwardly through the chamber 12 and are drawn off at the bottom through 40 the discharge passageway 20 of the kiln unit B. In order to properly direct the flow 45 of gases I provide suitable valves or dampers 64 adjacent the upper portion of the kiln chambers 12 at the point where the passageways 26 and 26a meet and dampers 66 adjacent 50 the lower portion of the kiln chambers. When these dampers 64 and 66 occupy the solid line positions shown in Figure 5, the gases from the combustion chamber 55 of the unit A will follow the path just described and in this way the heat employed in the unit A may also be utilized for treating the ware within the kiln unit B. Obviously, additional units might be coupled together without departing from the spirit 60 and scope of my invention. By actuating the dampers 64 and 66, the flow of hot gases might be reversed. That is to say, the heat supplied from the combustion chamber of the kiln unit B might be directed into association 65 with the ware of the unit A. Also

each unit may be operated independently of the other by merely adjusting the positions of the dampers. By employing the above described coupled arrangement, the hot gases from one kiln may be introduced under pressure within the adjacent kiln and thereby a marked saving in fuel is obtained. In other words, the exit hot gases from one kiln may be used for water-smoking or preliminarily heating the ware in the adjacent kiln. 70

The apparatus just described and the method capable of being practiced by the use thereof present numerous advantages over other types of apparatus and methods which have been brought to my knowledge. Some 75 of these distinct advantages may be summarized as follows: The ware is subjected to uniform heat conditions and hence a uniformly burned or heat treated product results; the capacity of the kiln is greatly increased by reason of the fact that no bag walls or pockets are provided therein; the introduction of air into the flue serves to temper the hot gases in a very efficient manner and provides a vehicle for drying purposes; the introduction of tempered hot gases under pressure at the upper central portion of the kiln chamber makes for uniform and complete diffusion of the hot gases 80 within the kiln chamber; the laning or localizing of heated gas areas is positively prevented; the provision of a flue having appreciable length insures complete combustion, and provides a convenient place for the introduction of vehicle air; by employing a 85 stoker mechanism of the type described in combination with the kiln, the smoke nuisance which has heretofore been experienced, will be abated because complete combustion is effected; and the described apparatus is 90 of simple and practical construction. 95

Having thus described my invention, what I claim as new and desire to secure by Letters Patent is:

1. In heat treating apparatus of the class described, a chamber for receiving a supply of ware to be treated, means for supplying heated gases, a flue for conducting said heated gases into said chamber, and means for introducing a supercharge of air within the flue for association with said heated gases. 110
2. In apparatus of the class described for heat treating ceramic materials and the like, a chamber for receiving a supply of ware to be heat treated, means for supplying heated gases, means for conducting said heated gases into the upper central portion of said chamber, and means for controlling the temperature of the heated gases supplied to said chamber. 120
3. In heating apparatus of the class described, a kiln having a chamber for receiving a supply of ware, means for supplying heated gases, an elongated flue connecting said gas supplying means with the kiln chamber. 125

- ber, and means for directing a supercharge of air into said flue for association with said heated gases.
4. In combination with a chamber of a kiln, a furnace for supplying heated gases, a flue connecting the top of the kiln with said furnace, and means for supplying air to said flue.
5. In combination with the chamber of a kiln, a furnace for supplying heated gases, a flue connecting said furnace with the upper portion of the kiln chamber, means for supplying air to said flue, a casing enclosing said furnace, and means for supplying air within said enclosure to maintain a pressure surrounding the furnace greater than the pressure within the furnace.
6. In heat treating apparatus of the class described, a dome-shaped kiln having a chamber for receiving ware to be treated, a furnace for supplying heated gases, a flue connecting said furnace with the upper central portion of said dome-shaped kiln, and means for controlling the temperature of the gases directed into said kiln.
7. In apparatus of the class described for heat treating ceramic materials and the like, a dome-shaped kiln having a chamber for receiving ware to be treated, a furnace for supplying heated gases, a flue connecting said furnace with the upper central portion of said dome-shaped kiln, and means for supplying air under pressure to said flue for association with the heated gases therein, whereby said heated gases will be effectively tempered and a vehicle for carrying off the moisture is provided.
8. In apparatus of the class described for heat treating ceramic materials and the like, a kiln chamber for receiving ware to be treated, an external furnace for generating heat, and means for conducting heated gases from said furnace into the upper central portion of the kiln chamber at a pressure above atmospheric pressure.
9. In apparatus of the class described for heat treating ceramic materials and the like, a heat treating kiln chamber, means for supplying heated gases at a pressure above atmospheric pressure, and means for introducing said heated gases into the upper portion of said kiln chamber.
10. In heat treating apparatus of the class described, a kiln chamber for receiving a supply of ware to be heat treated, an external furnace for supplying heated gases under pressure in excess of atmospheric pressure, and means for conducting said heated gases into said kiln chamber, whereby the pressure of the gases in said kiln chamber will be maintained above atmospheric pressure.
11. The method of heat treating ceramic materials which consists in placing the material within a chamber, introducing a supply of heated gases under pressure at the top of
- said chamber, uniformly diffusing said gases throughout the entire chamber and withdrawing said gases at the lower portion of said chamber.
12. The method of heat treating ceramic materials which consists in placing the material within a chamber, and treating said material with heated gases supercharged with air at a pressure above atmospheric pressure so as to obtain uniform diffusion of the gases within said chamber.
13. The method of heat treating ceramic materials which consists in placing material within a chamber, treating said material with heated gases at a pressure above atmospheric pressure so as to obtain uniform diffusion of the gases within said chamber, withdrawing heated gases from said chamber, and then employing said withdrawn gases for treating another quantity of ceramic material.
14. The method of heat treating ceramic materials which consists in placing material within a chamber, introducing a supply of heated gases at the top of said chamber, uniformly diffusing said gases throughout the entire chamber, withdrawing said gases at the lower portion of said chamber, and utilizing said withdrawn gases for heat treating another supply of ceramic material.
15. The method of heat treating ceramic materials which consists in placing the material within a chamber, introducing a supply of heated gases at the top of said chamber, uniformly diffusing said gases throughout the entire chamber, withdrawing said gases at the lower portion of said chamber, and then directing said withdrawn gases into the top of a second chamber containing a supply of ceramic materials.
16. In heat treating apparatus of the class described for heat treating ceramic materials and the like, a kiln chamber for receiving a supply of ware to be heat treated, a unitary external furnace providing the sole supply for heated gases, and means for directing heated gases from said unitary external source of supply into the upper portion of said chamber.
17. In an apparatus of the class described for heat treating ceramic materials and the like, a heat treating chamber for receiving ware to be treated, a unitary furnace for supplying all of the heated gases necessary for treating the ware, means for directing the heated gases from said furnace into the upper portion of the chamber, and means for directing a supply of air into association with said heated gases.
18. In apparatus of the class described for heat treating ceramic materials and the like, a heat treating chamber for receiving ware to be treated, an automatic stoker for supplying heated gases, and means for directing

the heated gases from said automatic stoker into said heat treating chamber.

19. In combination with the chamber of a kiln, an automatic stoker for supplying heated gases, and a flue connecting said automatic stoker with the upper portion of the kiln chamber, whereby gases from said automatic stoker may be employed for heat treating the ware within the kiln.

10 20. In combination with the chamber of a kiln, a furnace for supplying heated gases, a flue connecting said furnace with said kiln, and means for directing air into association with said heated gases at a point spaced from 15 said furnace and in an amount which is in excess of the amount of air required for combustion purposes within the furnace.

21. In combination with a chamber of a kiln, a furnace for supplying heated gases 20 to said chamber, a flue connecting said furnace with said kiln, and means for directing air into association with said heated gases in an amount which is in excess of the amount required for combustion purposes within the 25 furnace.

22. In combination with the chamber of a kiln, a furnace for supplying heated gases to said chamber, a flue connecting said furnace with the kiln chamber, a casing enclosing 30 said furnace, and means for supplying air within said enclosure to maintain a pressure surrounding the furnace greater than the pressure within the furnace.

35 23. In combination with the chamber of a kiln, a furnace for supplying heated gases, a flue connecting said furnace with the kiln chamber, means for supplying excess air for the heated gases, and a casing enclosing said furnace, the pressure within said enclosure 40 being greater than the pressure within the furnace.

24. In combination with the chamber of a kiln, an external furnace, said furnace being adapted to effect the complete and smokeless 45 combustion of bituminous fuel, and means for conducting smokeless, heated gases from said furnace into the kiln chamber for treating the ware within said chamber.

50 25. In combination with the chamber of a kiln, an external furnace, said furnace being adapted to effect the complete and smokeless combustion of bituminous fuel, means for conducting smokeless, heated gases from said furnace into the kiln chamber for treating the 55 ware within said chamber, and means for introducing air into association with the heated gases, which air is in excess of that required to complete combustion of the bituminous fuel within the confines of the furnace.

60 26. The method of heat treating ware within the chamber of a kiln, which consists in burning bituminous fuel in an external combustion chamber with the correct amount of 65 air for complete and smokeless combustion

within the confines of said chamber, tempering the hot gases given off from the combustion chamber to a degree required by the ware within the kiln, and then subjecting said ware to the tempered, heated gases.

70 27. The method of heat treating ware within the chamber of a kiln, which consists in burning bituminous fuel in an external furnace with the correct amount of air for complete smokeless combustion within the confines of said external furnace, so as to supply heated gases, diluting said heated gases with an excess supply of air to a degree required by the ware within the kiln chamber, and then subjecting said ware to said diluted, 80 heated gases.

75 In witness whereof, I have hereunto subscribed my name.

JOSEPH HARRINGTON.
